UNITED STATES PATENT OFFICE

2,426,523

CURRENT LIMITER

Julian Rogoff, New Rochelle, N. Y., assignor to
 Burndy Engineering Company, Inc., a corpora-
 tion of New York

Application January 14, 1943, Serial No. 472,423

2 Claims. (Cl. 200—113)

1

This invention relates to fusible devices for protecting electrical circuits from the detrimental effects of short circuit currents.

In aircraft, much of the electrical equipment is designed to use extremely heavy currents for short periods of time, perhaps for six to ten seconds. However, if such equipment were to carry currents of this magnitude for longer periods of time, the heat generated by the current might permanently damage the equipment and even cause a disastrous fire.

Accordingly, the primary object of my invention is to provide a current device which may be easily mounted on the structure of an airplane and on which the fusible link may be readily placed or replaced.

Another object of my invention is to provide a device which will be light in weight and small in size so that it will be suitable for aircraft use.

Still another object of my invention is to provide a fusible link which will carry electrical overloads for considerable periods of time, but which will clear very large overloads, such as those caused by dead short circuits, in a very short period of time.

Still another object of my invention is to provide a fusible link which will not be affected materially by relatively large variations in ambient temperature.

A further object of my invention is to provide a fusible link which will clear the electrical circuit without arcing or "sputtering."

Other objects are to provide a fusible element which will function as indicated, to which a flame-proof shell has been assembled in a substantially permanent manner, and which can be instantly replaced by a limiter and associated flame-proof shell; to provide a limiting device having terminal studs which can be assembled as a unitary assembly to the aircraft structure; to provide a limiter and flame-proof shell which can be detachably engaged to the assembly-supporting base; and to provide a device of the foregoing character which shall be adaptable to mass production methods, inexpensive to manufacture and simple to install.

I accomplish these and other objects and obtain my new results as will be apparent from the device described in the following specification, particularly pointed out in the claims, and illustrated in the accompanying drawing, in which:

Fig. 1 is a plan view of my device, partially in section.

2

Fig. 2 is a side view of the same, partially in section.

Fig. 3 is a cross-sectional view of my device taken along the line 3—3 in Fig. 2.

Fig. 4 is a cross-sectional view taken along the line 4—4 in Fig. 2.

Referring more particularly to the drawings, reference numeral 10 designates a moulded insulating tie bar having recesses 11 and 12, provided with center apertures 13 and 14 respectively. Extending through the apertures are bolts 15 and 16, their heads 17 and 18 positioned within their respective recesses 11 and 12. Spacer nuts 19 and 20 lock the bolts securely to the tie bar 10.

The limiter 21 comprises two apertured head sections 22 and 23 and integrally connecting fuse link 24, having a special shape for interrupting the circuit under predetermined conditions, as aforesaid. About the fuse link 24, two halves 25 and 26 of the flame-proof shell 27 are cemented, each of which halves are provided with two intermediate barriers 29 and 30 respectively, forming three compartments 31, 32 and 33 for containing the molten metal of the fuse link, and providing sufficient space for the expanded gases resulting from the circuit interruption.

The terminals 34 and 35 are mounted on the bolts 15 and 16, through apertures 36 and 37 in the terminal plates 38 and 39 respectively. The thicknesses of the terminal plates 38 and 39 and spacer nuts 19 and 20 are approximately equal to the thickness of the lower half 25 of the flame proof shell 27.

Clamping nuts 40 and 41 lock the limiter and the terminal plates to the tie bar to form a unitary assembly.

The sides of the tie bar 10 may be recessed as at 42, see Fig. 3, to receive the spring head of the clip 43 which supports the flame-proof shell 27 to the tie bar during the assembly. The two halves of the shell may be uncemented if the clip 43 is used.

The tie bar and assembly may be mounted on the mounting plate 44 by first interposing an insulating sheet 45 therebetween, perforated to receive the two flat head mounting screws 46 and 47, inserted into the apertured recesses 48 and 49 of the upper surface of the tie bar. The mounting screws extend through apertured nut plate 50, and the special vibration-proof lock nuts 51 and 52 are formed thereon.

It will be evident by the described construction that the limiter and flame-proof shell may be attached to and removed from the supporting tie block as a single unit.

The construction illustrated accomplishes the further objects of my invention. The device is adaptable to mass production methods and is simple to install. The particular link illustrated is not affected by large variations in ambient temperatures and the electric circuit can be quickly cleared without arcing or sputtering. Further, the link is designed to carry heavy currents for predetermined periods of time, without fusing.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments herein shown and described are only some of the many that can be employed to attain these objects and accomplish these results.

What I claim and desire to secure by Letters Patent, is as follows:

1. A current limiter for detachably securing a pair of conductors thereto, said current limiter comprising a metallic fuse link having two exposed ends provided with detachable engaging means, and an intermediate fusible element made of the same piece of metal as the two ends; a

flame-proof enclosure secured to the fuse link, permitting the two exposed ends of the fuse link to extend therefrom; an insulating supporting means positioned adjacent the fuse link, having a securing means positioned at each end of the insulated supporting means for simultaneously and detachably securing a conductor and an end of the fuse link to each other and both the conductor and the fuse link to the insulating supporting means by said securing means.

2. The current limiter of claim 1 wherein the flame-proof enclosure is permanently secured to the fuse-link with exposed ends, by non-metallic means.

JULIAN ROGOFF.
